United States Patent Office

Des. 208,560
Patented Sept. 12, 1967

208,560

TOY POWER TOOL

Joseph J. Wetherell, 210 W. 89th St.,
New York, N.Y. 10024

Filed Aug. 19, 1966, Ser. No. 3,534

Term of patent 14 years

(Cl. D34—15)

Fig. 4

Fig. 3

FIG. 5

FIG. 6

FIG. 1 is a front elevational view of a toy power tool embodying my new design;

FIG. 2 is a side elevational view of the toy power tool;

FIG. 3 is a rear elevational view of the toy power tool;

FIG. 4 is a side elevational view of the toy power tool taken from the opposite face illustrated in FIG. 2;

FIG. 5 is a top plan view of the toy power tool; and

FIG. 6 is a bottom plan view of the toy power tool.

I claim:

The ornamental design for a toy power tool, as shown.
